[57] CLAIM

The ornamental design for a cordless drill, as shown and described.

DESCRIPTION

FIG. 1 is a perspective view of the cordless drill showing our new design;

FIG. 2 is a side elevational view of one side thereof;

FIG. 3 is a top view thereof;

FIG. 4 is a side elevational view of the other side thereof;

FIG. 5 is a bottom plan view thereof;

FIG. 6 is a front elevational thereof;

FIG. 7 is a rear elevational view thereof;

FIG. 8 is a perspective view of an alternative battery pack in the cordless drill of FIG. 1; with the drill portion of the claimed design being omitted for ease of illustration;

FIG. 9 is a side elevational view of one side of the battery pack, the other side being identical;

FIG. 10 is a front view of the battery pack of FIG. 8; and, FIG. 11 is a rear view of the battery pack of FIG. 10.

The broken line showing in FIG. 1 is for illustrative purposes only and forms no part of the claimed design.
